UNITED STATES PATENT OFFICE.

ELBERT E. HAWKINS, OF UNADILLA, NEW YORK.

DOOR-FASTENING DEVICE FOR SILOS.

1,132,774.

Specification of Letters Patent. Patented Mar. 23, 1915.

Application filed June 13, 1914. Serial No. 844,858.

To all whom it may concern:

Be it known that I, ELBERT E. HAWKINS, a citizen of the United States, and resident of Unadilla, county of Otsego, and State of New York, have invented an Improvement 5 in Door-Fastening Devices for Silos, of which the following is a specification.

This invention relates to silos, and more particularly to an improved fastening device 10 for securing and locking a removable silo door, so that the door is positively held in closed position to form substantially an air-tight closure for the opening with which it is adapted to coöperate.

15 It has for a further object to provide a silo door of removable type which is adapted to be inserted in the opening, provided for the purpose, from the interior of the silo and drawn into position through the medium of 20 a locking mechanism, one part of which embodies the rung or rungs forming the ladder for the side of the silo.

25 My invention also comprehends details of construction which, together with the features above specified, will be better understood by reference to the drawings, in which:

30 Figure 1 represents a front elevation of a portion of a silo showing the doors and fastening devices embodying my invention; Fig. 2 represents one of the fastening devices in unlocked position upon a door; Fig. 3 represents a side elevation of the same; Fig. 4 represents a section on line 35 4—4 of Fig. 1, showing a door and adjacent adjuncts in section.

1 designates the body or frame of the silo which in the preferred form is of the customary cylindrical shape bound together at 40 suitable points by metal hoops 2 provided with the usual adjusting nuts 3.

4 designates the side timbers forming a vertical opening throughout substantially the length of the silo and which timbers are 45 connected at spaced intervals by the sill members 5, thereby forming a plurality of openings one above the other, each of which is closed by a removable door 6 so that any part of the interior of the silo is made readily accessible.

In connection with my improved securing means for maintaining the doors in operative position it will be noted that the side timbers, as well as the sills, are rabbeted and beveled as shown at 7, said bevels converging toward the outside of the silo. The doors 6 are correspondingly beveled to fit within the beveled openings, as will be understood. It will thus be seen that each door is adapted to be inserted in its opening 55 from the interior of the silo and the following description of the fastening devices will disclose the fact that the said doors are drawn tightly into place so that the beveled construction insures the close fit desired. 60 As all of the doors are substantially similar in construction and carry like fastening devices, I shall for the purpose of this disclosure confine the description to one door 65 and its locking adjuncts.

70 8 designates a pair of latch members each pivoted at a suitable point to the door as shown at 9, and each having a substantially arched or semi-spherical portion from which a leg or brace member 10 and a tongue 11 extend toward the door and form an integral part of the arched body part. The body portion of each latch is furthermore provided with a suitable slot 12, here shown by way of example as 75 curved and serving to receive one leg of the bail 13. This bail is substantially U-shaped and is preferably provided with bent ends 80 14 which are adapted to fit within a U-bolt 15 suitably fixed to the door 6, this connection being a hinged or pivoted 85 connection to allow free movement of the bail. It will be understood that the central portion of the bail in one position of the parts forms the foot-piece or rung of a ladder for the side of the silo.

90 16 designates a keeper adapted to receive the tongue 11 of the latch 8, this keeper being fixed to the door 6 adjacent one of the side timbers 4 and, as will be seen from Fig. 95 3, is inclined with respect to the door so that the distance of the lower end from the door is substantially less than the upper end. The operation of this construction will be apparent when it is noted that the tongue 100

11 after passing through the keeper 16 overlaps the face of the timber 4 and consequently when the latch is swung downwardly into locking position, as shown in 5 dotted lines in Fig. 2, the obvious result is to clamp or draw the door into its opening in a positive manner.

Attention is directed to the fact that when the latch is in its locking position the brace 10 member 10 takes a position vertically below the contact point of the bail 13 with the bottom of the slot 12, and as this brace member rests in contact with the door it will be evident that the weight carried by the bail 15 when used as a ladder is distributed and the strain on the latch better sustained.

It is thought in view of the simplicity of the device that it is unnecessary to enlarge materially upon the operation of the device, 20 but it will be noted that the slot 12 in addition to forming a guide for the bail, has the very important function of acting as a cam whereby movement of the bail toward the top of the silo causes the latch to swing inwardly out of engaging position with the side timbers 4 so that the door may be readily removed if desired. On the other hand, the slot also serves to impart movement to the latch when the bail is swung 25 downwardly to its horizontal position, thus not only bringing the latch into locking position but also through its coöperation with the inclined keeper forcing the door to its sealed position, where it is positively locked.

30 It will now be apparent that I have devised a novel and useful construction which embodies the features of advantage enumerated as desirable, and while I have in the present instance shown and described 35 the preferred embodiment thereof which has been found in practice to give satisfactory and reliable results, it is to be understood that I do not restrict myself to the details, as the same are susceptible of modification 40 in various particulars without departing 45 from the spirit or scope of the invention.

Having now described my invention, what I claim and desire to protect by Letters Patent is:—

50 1. In a device of the character stated, a suitable frame providing an opening the sides of which are beveled toward the outer side of said frame, a door correspondingly beveled and adapted to seat within said 55 opening, keepers fixed to said door at opposite sides thereof, and providing a face inclined to said door, a latch for each keeper pivoted to said door and having a tongue adapted to pass between said keeper inclined 60 face and the door and overlap said frame, each latch having an arched portion provided with a cam slot, and a bail pivoted at each end to said door and passing through the respective cam slots of said latches

whereby movement of said bail in one direction forces said latches into engagement with said inclined faces to draw said door outwardly into the opening provided. 65

2. In a device of the character stated, a suitable frame providing an opening the 70 sides of which are beveled toward the outer side of said frame, a door correspondingly beveled and adapted to seat within said opening, keepers fixed to said door at opposite sides thereof, and providing a face inclined to said door, a latch for each keeper pivoted to said door and having a tongue adapted to pass between said keeper inclined face and the door and overlap said frame, each latch having an arched portion 75 provided with a cam slot, a bail pivoted at each end to said door and passing through the respective cam slots of said latches whereby movement of said bail in one direction forces said latches into engagement 80 with said inclined faces to draw said door outwardly into the opening provided, and a brace member between said door and each latch for supporting said latch and bail when said bail is used as the rung of a 85 ladder.

3. In a device of the character described, a door frame having an opening larger on the inside than on the outside, combined with a door adapted to close said opening 90 from inside outward, a pair of latches hinged to the door and respectively extending outward on opposite sides therefrom to engage the door frame upon its outer side, said latches each having a slotted arch 95 shaped portion and a downwardly extending strut from said arch shaped portion sliding upon the front of the door and acting as a brace, a U-shaped bail having its arms hinged to the door and extending through 100 the slots of the latches to move them in locking the door in position as well as in opening the same and also supported by the arch shaped portions and struts thereof so as to 105 perform the function of a round in a ladder, and a keeper for each latch secured near the side edges of the door and extending over the latch arms. 110

4. In a device of the character described, a door frame having an opening larger on the inside than on the outside, combined with a door adapted to close said opening 115 from inside outward, a pair of latches hinged to the door and respectively extending outward on opposite sides therefrom to engage the door frame upon its outer side, said latches each having a slotted arch shaped portion and a downwardly extending strut from said arch shaped portion 120 sliding upon the front of the door and acting as a brace, a U-shaped bail having its arms hinged to the door and extending through 125 the slots of the latches to move them

in locking the door in position, as well as in opening the same, and also supported by the arch shaped portions and struts thereof so as to perform the function of a round in 5 a ladder, and a keeper for each latch secured near the side edges of the door and extending over the latch arms, said keepers having their inner surfaces made cam shaped, and having their lower portions

closer to the door surface than their upper 10 portions.

In testimony of which invention, I hereunto set my hand.

ELBERT E. HAWKINS.
